DESIGN FOR A JEWELRY FINDING

John Rubel, New York, N. Y.

Application January 1, 1945, Serial No. 117,206

Term of patent 7 years

(Cl. D45—1)

To all whom it may concern:

Be it known that I, John Rubel, a citizen of the United States, residing in New York city, in the county of New York and State of New York, have invented a new, original, and ornamental Design for a Jewelry Finding, of which the following is a specification, reference being had to the accompanying drawing, forming part thereof.

Fig. 1 is a front elevational view of a jewelry finding showing my design, and

Fig. 2 is the side view thereof.

I claim:

The ornamental design for a jewelry finding, substantially as shown.

JOHN RUBEL.
